UNITED STATES PATENT OFFICE.

EDWARD FERGUSON CHANCE, OF SANDFORD ST. MARTIN, ENGLAND, ASSIGNOR TO CHANCE BROTHERS AND CO., LIMITED, OF GLASS WORKS, NEAR BIRMINGHAM, ENGLAND.

DESIGN FOR PLATE-GLASS.

42,523.

Specification for Design.

Patented May 14, 1912.

Application filed October 4, 1911. Serial No. 652,858. Term of patent 14 years.

To all whom it may concern:

Be it known that I, EDWARD FERGUSON CHANCE, a subject of the King of Great Britain, residing at Sandford Park, Sandford St. Martin, Oxfordshire, England, have invented a certain new, original, and ornamental Design for Plate-Glass, of which the following is a specification, reference being had to the accompanying drawing, forming part thereof.

Figure 1 is a plan view of a piece of plate glass showing my new design and Fig. 2 is an end view of the same.

The design is a repeat pattern made up of three irregular convex waved surfaces *a*, *b*, *c*, separated by a channel or groove *d*. The

irregular convex waves *a*, *b* each have within them an irregular hollow or concave depression marked respectively *a*¹, *b*¹ and the irregular convex wave *c* has within it two separated irregular hollow or concave depressions marked *c*¹, *c*² respectively.

I claim:—

The ornamental design for plate glass as shown and described.

In testimony whereof I have hereunto set my hand in presence of two subscribing witnesses.

EDWARD FERGUSON CHANCE.
